US0D1083936S

(12) **United States Design Patent** (10) **Patent No.:** **US D1,083,936 S**
(45) **Date of Patent:** **** Jul. 15, 2025**

(54) **DEVICE COVER**

(71) Applicant: **Amazon Technologies, Inc.**, Seattle, WA (US)

(72) Inventors: **Martin Gschwandtl**, San Francisco, CA (US); **Bernhard Wildner**, San Francisco, CA (US); **Ippei Matsumoto**, Daly City, CA (US)

(**) Term: **15 Years**

(21) Appl. No.: **29/965,609**

(22) Filed: **Sep. 27, 2024**

Related U.S. Application Data

(63) Continuation of application No. 29/867,692, filed on Nov. 3, 2022, now Pat. No. Des. 1,050,135.

CLAIM

The ornamental design for a device cover, as shown and described.

DESCRIPTION

FIG. 1 is a top, front, right-side perspective view of a device cover;

FIG. 2 is a bottom, back, left-side perspective view thereof;

FIG. 3 is a front view thereof;

FIG. 4 is a back view thereof;

FIG. 5 is a left-side view thereof;

FIG. 6 is a right-side view thereof;

FIG. 7 is a top view thereof; and,

FIG. 8 is a bottom view thereof.

The dashed broken lines depict portions of the device cover that form no part of the claimed design.

1 Claim, 8 Drawing Sheets
